(57) **CLAIM**

I claim the ornamental design for a gauge-integrated tweezers for teeth alignment, as shown and described.

DESCRIPTION

FIG. 1 is a front perspective view of a gauge-integrated tweezers for teeth alignment, showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is an enlargement of FIG. 4; and,
FIG. 9 is an enlargement of FIG. 5.
